Primary Examiner — Cathron Brooks*Assistant Examiner* — Kevin Rudzinski(74) *Attorney, Agent, or Firm* — Heslin Rothenberg Farley & Mesiti P.C.(57) **CLAIM**

The ornamental design for a light fixture crystal mounting arm, as shown and described.

DESCRIPTION

FIG. 1 is a perspective view of the light fixture crystal mounting arm of the present design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof; and,

FIG. 7 is a bottom plan view thereof.

The broken line illustration of a crystal and portion of the light fixture crystal mounting arm illustrate environmental structure and forms no part of the claimed design.
